E. H. REINHOLD

HANDSAW

Filed Jan. 15, 1924

Inventor
EDWARD HENRY REINHOLD

By Murray & Gugelter

Attorneys

UNITED STATES PATENT OFFICE.

EDWARD HENRY REINHOLD, OF CINCINNATI, OHIO.

HANDSAW.

Application filed January 15, 1924. Serial No. 686,400.

To all whom it may concern:

Be it known that I, EDWARD HENRY REINHOLD, a citizen of the United States of America, and a resident of Cincinnati, in the county of Hamilton and State of Ohio, have invented a new and useful Improvement in Handsaws, of which the following is a specification.

An object of my invention is to provide a handsaw having embodied therein several of the more common implements which are used in laying out work.

Another object is to provide a device of this kind which will eliminate the necessity of handling a square, rule, and a 45-degree angle or miter square.

Another object is to provide a device of this kind wherein the saw is not made cumbersome or awkward of handling by having the various measuring implements embodied therein.

These and other objects are attained by the means described herein and disclosed in the accompanying drawing, in which:

Fig. 1 is a fragmental elevation of the handsaw of my invention.

Fig. 2 is a top view of Fig. 1, and

Fig. 3 is a bottom view of Fig. 1.

The saw of my invention comprises the ordinary cutting blade 4, along the straight edged top of which are graduations 5 in order to provide a measuring scale. The handle 6 is secured to the blade by means of the usual securing screws 7, the blade 4 being set into the kerf or slot 8 in the usual manner. The forward edge 9 of the handle 6 is arranged at an angle of 90 degrees to the top edge of the blade 4. A binding strip 10 is secured by any suitable means such as

screws 11 upon the forward edge 9 of the handle and is continued around the bottom edge 12 of the handle. The binding strip 10 is turned inwardly adjacent the blade at an angle of 90 degrees; the kerf 8 being widened in order to permit the flange 13 thus formed to be fully seated therein. The strip 10 binds the forward edge of the handle 6 on one side of the blade and the entire bottom surface of the handle from a point beginning at the edge 14 of the kerf. A supplemental binding strip 15 is brazed to the strip 10 at point 14 and binds the other forward edge of the handle. The binding strips 10 and 15 having flanges 13 supple-

ment the clamping action of the screws 7 for securing the blade 4 against relative mo-

tion in the handle. The rear end 16 of the cutting blade 4 is cut at an angle of 45 degrees to the bottom edge of the handle 6.

It will be noted that the above described construction provides a square, a miter square, and a scale, all of which are constantly used with a saw. The implement thus formed has no cumbersome projections to render its use difficult.

As described above my invention is applied normally to cross-cut saws. In ripsaws it would be necessary only to provide the edge 9 and binding 10 therefor for a comparatively short distance and to provide the graduations 5 extending therefrom in order to gage a line along a board to be ripped.

The blade 4 is fixedly secured to the binding strip 10 by any suitable means such as rivets 20. Any number of rivets may be employed at any desired places.

What I claim is:

1. In a handsaw the combination with a straight backed saw blade, a slotted handle having straight forward edges and straight bottom edges, a flanged binding strip engaging the bottom of the handle and one side of the forward edge of the handle, a supplemental flanged binding strip secured upon the forward edge of the handle on the other side of the blade, the flanges on the binding strips engaging the opposite sides of the cutting blade, the rear end of the cutting blade adjacent the cutting edge thereof being disposed at an angle of 45 degrees to the bottom of the handle, means for securing the binding strips upon the handle, and means for securing the handle to the cutting blade.

2. In a handsaw the combination of a handle having a straight edged forward end and a straight edged bottom, of a cutting blade secured upon the handle and having its top edge disposed at an angle of 90 degrees to the forward edge of the handle and its rear edge disposed at an angle of 45 degrees to the bottom of the handle, graduations along the blade adjacent its top edge, and a binding strip secured to the forward and bottom edges of the handle and disposed at an angle of 90 degrees to the sides of the cutting blade.

In testimony whereof, I have hereunto subscribed my name this 11th day of January, 1924.

EDWARD HENRY REINHOLD.
